FIG. 4

FIG. 5

FIG. 6

FIG. 7

FIG. 8

FIG. 9

FIG. 10

FIG. 1 is a front view of a bench showing my new design;

FIG. 2 is a side view thereof;

FIG. 3 is an enlarged cross-sectional view taken through line 3—3 of FIG. 2;

FIG. 4 is an enlarged cross-sectional view taken through line 4—4 of FIG. 2;

FIG. 5 is an enlarged cross-sectional view taken through line 5—5 of FIG. 2;

FIG. 6 is an enlarged cross-sectional view taken through line 6—6 of FIG. 2;

FIG. 7 is an enlarged cross-sectional view taken through line 7—7 of FIG. 2;

FIG. 8 is an enlarged cross-sectional view taken through line 8—8 of FIG. 2;

FIG. 9 is a rear elevational view thereof; and

FIG. 10 is a front perspective view thereof.

I claim:

The ornamental design for a bench, substantially as shown.
